DRAFTING APPARATUS FOR
TEXTILE FIBERS

George V. Sumner, Columbia, S.C., assignor to Sumner Company, Inc., a corporation of South Carolina
Continuation-in-part of application Ser. No. 436,580, Mar. 2, 1965. This application Nov. 17, 1966, Ser. No. 595,168
21 Claims. (Cl. 19—243)

ABSTRACT OF THE DISCLOSURE

The combing and drafting of textile fibers, particularly woolen and synthetic fibers of various staple lengths such, for example, as from two to ten inches in length by a main rotary pin drum with which one or more pin worker rolls cooperate to engage the fibers and comb and draw them as they are fed through the machine by the grip of faster traveling delivery rolls assisted by the pin rolls as they engage the fibers.

Cross reference to related application

This invention is a continuation-in-part of my application, Ser. No. 436,580, filed Mar. 2, 1965, and now abandoned.

Background of the invention

In the processing of textile fibers of the staple above referred to, gill boxes with reciprocating needle bars are most generally used. These machines are relatively complicated and expensive and limited in their speed of operation by reason of their reciprocating motions. Also a plurality of these machines are required in the processing of fibers to a point accomplished by the present invention in a single apparatus. Other machines of various forms have been attempted but for one reason or another have never been generally used.

Summary

I have provided a plurality of heads each of which, as shown in FIG. 5, has a rotary main large drum or cylinder covered with card clothing, and I have led to and about a guide across the face of the cylinder and below its axis, material which will extend about the cylinder to a greater extent than half of its circumference, and again at a low point with reference to the cylinder, I have provided a delivery means which travels at a speed much higher than the surface speed of the cylinder so as to draw the fibers from the cylinder at a faster rate than the cylinder is traveling and feeding the fibers, thus attenuating the fibers something in the ratio of as 1 is to 3 to 10. One or more relatively smaller working rolls are provided with card clothing and located at a predetermined point or points about the main cylinder which provide a means to give an earlier drafting action to the fibers in one or more stages, followed by the final drafting by the delivery rolls. A plurality of these heads are arranged in parallel as shown in FIG. 1 to receive a plurality of card slivers while the delivery from a plurality of heads is fed in parallel to a final head which delivers to one or more coilers or top making mechanisms.

Description of the drawings

FIG. 1 is a diagrammatic plan view of the machine;
FIG. 2 is a diagrammatic plan view of the drive for the machine;

FIG. 3 is a view similar to FIG. 1 of a modification;

FIG. 4 is an elevation of FIG. 3;

FIG. 5 is a side elevation largely diagrammatic illustrating the essential parts of one head of the invention;

2

FIG. 6 is an elevation of a detail showing the loading of the delivery means from one of the heads; and

FIG. 7 is a perspective view of a detail for adjusting the working roll.

Description of the preferred embodiments

With reference to the drawings in FIG. 1, there are a plurality heads, here shown as four, 10, 11, 12, 13, although this number may be varied, each of which receives a plurality of card slivers, here shown as six, 15, 16, 17, 18, 19, 20 from a yarn converter such for example as a card machine. Each of the four heads delivers its sliver or work as at 22, 23, 24, 25 which slivers are turned about posts 26, 27, 28, 29, or other means to align the sliver so as to be fed in generally parallel relation as at 30, 31, 32, 33 into one or more heads 35 which is so driven that there is no slack in any of the slivers fed thereto. From this head 35 or heads the work may emerge as a single drafted end and is coiled by a coiler head or top making equipment 36 into a can or barrel 37.

In some cases as shown in FIGS. 3 and 4, instead of arranging to lead the combed and drawn fibers from each of the heads 10, 11, 12 and 13 as shown in FIG. 1, I pass the combed and drawn fibers from each of these heads through a pair of guide posts 110 and 111 and then over a roll 112 which is inclined at about 45° to the path of travel, passing these fibers over the top of the roll and around the roll so as to extend them as at 113 at right angles to their path from the guides 110, 111. The drawn fibers from each of the heads are similarly arranged. However, the fibers from these four heads are arranged in two groups so that the fibers 113a coming from head 11 are superimposed upon the fibers 113 from head 10. Likewise, the fibers 113c emerging from the head 13 are superimposed upon the fibers 113b from head 12 (as seen in FIG. 4). The fibers of the two groups are somewhat laterally arranged as seen in FIG. 3 and the fibers of the first group are above and spaced from the fibers of the second group so that the fibers of the two groups do not touch. Guides 118 and 119 assist in the separation of the groups. The fibers in these two groups with their layers in this superimposed relation then enter a head 35 as shown in FIGS. 3 and 4 with one layer over the other rather than one layer horizontally beside the other as shown in FIG. 1, and these two groups of fibers are again combed and drawn in the head 35 in spaced relation axial of the head 35. In this case I have chosen to guide the fibers so that one half of the fibers or one group of fibers pass into a condenser tube 114 and coiler 115 and the other half or other group of the fibers pass into the condenser tube 116 and the coiler 117. The processes of FIGS. 1 and 3 are similar except for the vertical and horizontal arrangement of the fibers.

Each of the heads 10, 11, 12, 13 and 35 is essentially the same and provides a combing and attenuation of the fibers of the slivers fed through it and may be best described with reference to FIG. 5 where the work is designated generally 40 and is led in about a guide or rod 41 having a fixed cylindrical surface, thence over a main cylinder or drum 42 covered as at 43 with card clothing having pins 44 extending therefrom and inclined rearwardly from a radius advancing in the direction of surface movement. This card clothing may be canvas backed or metallic with the pins substantially one quarter of an inch protrusion beyond its base. The work material of some thickness is disposed at the ends of the pins and then led to be engaged by one or more worker pin rolls 45, 45' and then to a delivery means designated generally 46. The delivery means comprises a pair

of steel fluted rolls 47 and 48 with a roll 49 covered as at 50 with resilient rubber which is urged toward the spaced fluted rolls 47 and 48. The material is delivered as at 51. Each of the working rolls 45 or 45' is covered with card clothing 52 of the same general character as the card clothing 43 and 44 and having spikes or pins 53 similarly inclined rearwardly. The position of each worker roll is such that it is spaced from the main cylinder by a gauged distance dependent on the character of the work.

It will be noted that the material is fed in at substantially point 55 where it is tangent to the guide 41 and is fed from the head at substantially point 51 or 56 where it contacts with the upper roll 49, 50 of the delivery means. The pin cylinder 42 is offset from a straight line between the feeding-in means and the delivery means by the axis of roll 42, being well above a straight line between these two parts so that the work will be disposed about a greater than half the circumference of the pin drum 42, thus providing a sufficient contact of the pins with the work even though riding on the ends of the pins so as to cause a feeding of the work into the machine while also providing a sufficient holdback for the work being urged into the pins so that the drafting and delivery means 46 will by reason of its faster surface speed draw the fibers one from the other and deliver them anywhere from three to ten times faster than they are fed into the head or heads.

A drafting and combing operation occurs by reason of working pin rolls 45 operating at a surface speed slower than the surface speed of the main cylinder or roll 42. There may be two working pin rolls 45, 45' such as shown in FIG. 5, and when there are two they will operate at different surface speeds with the first one at a slower surface speed than the subsequently operating one. It is found that the fibers as led onto the main roll 42 will remain substantially at the ends of the pins and extend radially outwardly of the pins on the main roll. The first working pin roll 45 with which the fibers engage will tend to pull the fibers away from the main roll and into the pins of the slower operating working roll at 57, thus causing a drawing of the fibers through the pins of the first working roll 45 to obtain a combing and drafting action. Similarly, the second working roll 45' will pick up the fibers as they leave the first working pin roll and are carried by the main cylinder 42 and are still on the surface or ends of the pins of the main cylinder, and although the second working roll 45' is traveling at a rate faster than the first working pin roll, it is still at a rate slower than the main pin roll 42. Consequently, a similar action will occur by reason of the fibers being picked up by the slower second working pin roll 45' with the fibers entering the pins at 58 of this slower working pin roll 45' and again receiving a drafting and combing action. However, as the fibers leave the last of the working pin rolls, the position of the delivery rolls is such that the fibers are then drawn into the pins of the main pin roll as at 59, and as the delivery mechanism is traveling faster than the surface speed of the main pin roll, the fibers will be drawn through the pins of the main pin roll and will be combed and drafted again. The ratio of surface speeds of the pin rolls may be as 17 is to 12.

Three drafting and combing action thus occur with two worker rolls, there being one additional combing and drafting action than the number of worker rolls as 45, 45'.

The rotary pin cylinder or drum 42 and the fluted steel rolls 47, 48 are mounted in suitable fixed bearings. The rubber covered roll 49 is pressed toward the fluted rolls 47, 48 by springs 65 engaging pivoted levers 66 which bear on the ends 67 of the roll 49. The bearings 71 for the working pin rolls have an upward projection 72 passing through a slot 73 in a plate 74. This projection 72 is provided with a threaded bore which receives the screw 75 mounted in bearings 76 and 77 enabling it to be rotated but not moved axially. Thus, when the screw 75 is rotated which may be by means of a head 78, the bear-

ing 71 will be moved along the slot 73 to move the working pin roll toward or from the main cylinder 42. In all cases, however, the working pin roll will have its teeth clear the teeth of the main pin roll a predetermined gauged distance dependent on the character of the work.

A drive for the machine may be provided as shown in FIG. 2 from motor 80 to the right angularly extending shafts 81, 82 and thence to the heads. Head 35 is belt or chain driven as at 83 to the front fluted roll 48 on shaft 84; thence by gears 85, 86, 87 drives rear fluted roll 47, and from shaft 84 drum 42 is driven by gears 88, 89, 90. The coiler is driven by positive means 91 from shaft 84.

A similar drive occurs for the four parallel heads by chain 95 or other positive means to the driving shaft 96 upon which all of the front fluted rolls of the four heads are mounted, while all rear fluted rolls of the four heads are driven by shaft 97 through gears 98, 99, 100, and all main pin drums are driven on shaft 101 driven by gears 102, 103, 104 from shaft 96.

I claim:

1. In a drawing frame for textile slivers, a guiding surface with which the entering work engages, a driven pin cylinder, delivery rolls for gripping and delivering the work from the cylinder, said pin cylinder being of a diameter substantially larger than the diameter of the delivery rolls and offset from a straight line between said guiding surface and delivery rolls sufficiently to provide an arc of work contact greater than 180° to force the work into the pin cylinder and over the upper surface of which pin cylinder the work extends and by which the work is fed, said delivery rolls having a surface speed greater than the surface speed of the pin cylinder to attenuate the slivers between the pin cylinder and the delivery rolls.

2. In a drawing head for textile slivers as in claim 1 wherein the pins on said cylinder are of the type of card clothing.

3. In a drawing head for textile slivers as in claim 1 wherein a working roll having pins is located at a gauged distance from the pins of the pin cylinder and is adjacent the attenuation of the slivers by the delivery means.

4. In a drawing head for textile slivers as in claim 3 wherein the pins on said working rolls are of the type of card clothing.

5. In a drawing head for textile slivers as in claim 3 wherein the working roll travels at a surface speed slower than the surface speed of the pin cylinder.

6. In a drawing head for textile slivers as in claim 3 wherein there are a plurality of working rolls traveling at a surface speed slower than the surface speed of the pin cylinder.

7. In a drawing head for textile slivers as in claim 3 wherein there are a plurality of working rolls traveling at a surface speed slower than the surface speed of the pin cylinder and at different surface speeds from each other.

8. In a drawing frame for textile slivers, a main driven pin cylinder having pins extending therefrom, means for guiding the slivers to said cylinder, delivery means for gripping and delivering the slivers from the cylinder, working rolls having pins located at a gauged distance from the pins of the main cylinder and all of said working rolls being closer to the delivery means than to said guiding means, said working rolls traveling at a surface speed slower than the surface speed of the main cylinder and at different surface speeds from each other.

9. In a drawing frame as in claim 8 wherein means is provided for driving the work contacting surface speed of the delivery means greater than the work contacting surface speed of the main cylinder to draw the fibers thru the pins of the main cylinder.

10. A drawing frame for textile slivers comprising a pair of gauged spaced rotating pin surfaces, means for rotating said pin surfaces at different speeds, said faster pin surface providing feeding pins engaging the slivers and drawing them through the pins of the slower moving

pin surface for drafting the slivers and means subsequently engaging the drafted slivers and moving the slivers faster than the surface speed of the feeding pins for drawing the slivers through the pins of the feeding surface to obtain a second drafting of the slivers.

11. In a drawing frame for textile slivers, a main driven pin cylinder having pins extending therefrom, means for driving the pin cylinder, means for guiding slivers fed to said cylinder, a working roll having pins gauged from the pins of the main cylinder, means for driving said roll at a surface speed less than the surface speed of the main cylinder positioned to engage the slivers so that the slivers are drawn therethrough, means to deliver slivers from the main cylinder at a surface speed greater than the surface speed of the main cylinder and at a location to draw the slivers through the pins of the main cylinder.

12. In a drawing frame as in claim 11 wherein there are a plurality of working rolls.

13. In a drawing frame for textile slivers, a main driven pin cylinder having pins extending therefrom, means for driving said cylinder, means for guiding slivers fed to said cylinder, a working roll having pins gauged from the pins of the main cylinder, said pins on the main cylinder and working roll being inclined rearwardly from a radius advancing in the direction of surface movement thereof, means for driving said working roll in the opposite direction of rotation and at a surface speed less than the surface speed of the main cylinder, said working roll being positioned to engage the slivers so that the slivers are drawn through the pins of the working roll, means to deliver slivers from the main cylinder at a surface speed greater than the surface speed of the main cylinder and at a location to draw the slivers through the pins on the main cylinder.

14. In a drawing frame as in claim 13 wherein there are a plurality of working rolls. 35

15. A drafting system comprising a plurality of heads each of which is adapted to receive a plurality of slivers and a second head adapted to directly receive the work delivered from said plurality of heads, each of said heads being similar and comprising a main pin cylinder and a working roll to comb and attenuate the slivers received, and delivery rolls to draw the sliver thru the pins of the main pin cylinder, said last head delivering at least one end of the blended and drafted slivers.

16. A drafting system as in claim 15 wherein the said second head is driven relative to said plurality of heads to maintain tension on the work delivered from said plurality of heads.

17. A drafting system as in claim 15 wherein the work delivered from the plurality of heads is guided in a parallel relation to said second head.

18. A drafting system as in claim 15 wherein said last head delivers a plurality of ends of blended and drafted fibers.

19. In a drawing frame for textile slivers, a main driven pin cylinder having pins extending therefrom, means for guiding the slivers to said cylinder, delivery means for gripping and delivering the slivers from the cylinder, working rolls having pins located at a gauged distance from the pins of the main cylinder and adjacent the delivery means, said working rolls traveling at a surface speed slower than the surface speed of the main cylinder and the working roll nearest the delivery means traveling at a surface speed greater than the surface speed of a preceding working roll.

20. In a drawing frame for textile slivers, a main driven pin cylinder having pins extending therefrom, means for guiding the slivers to said cylinder, delivery means for gripping and delivering the slivers from the cylinder, working rolls having pins located at a gauged distance from the pins of the main cylinder and adjacent the delivery means, said working rolls traveling at a surface speed slower than the surface speed of the main cylinder and the surface speed of each working roll being progressively slower as it is more distant from the delivery means.

21. The process of treating condensed homogeneous slivers as taken from a yarn converting machine which comprises engaging the slivers with feeding pins and moving said pins to draw the slivers through other similar pins and then engaging the slivers and drawing the slivers through said feeding pins to straighten and attenuate the fibers at each drawing step.
